UNITED STATES PATENT OFFICE.

CHARLES B. SIMMONS, OF BRISTOL, CONNECTICUT, ASSIGNOR TO THE NEW DEPARTURE MANUFACTURING COMPANY, OF BRISTOL, CONNECTICUT, A CORPORATION OF CONNECTICUT.

CLUTCH MECHANISM.

Application filed June 13, 1924. Serial No. 719,800.

To all whom it may concern:

Be it known that I, CHARLES B. SIMMONS, a citizen of the United States, residing at Bristol, county of Hartford, State of Connecticut, have invented a certain new and useful Clutch Mechanism, of which the following is a full, clear, and exact description, such as will enable others skilled in the art to which it appertains to make and use 5 the same, reference being had to the accompanying drawings, forming part of this specification.

My invention relates to clutch mechanisms, especially as embodied in coaster 15 brakes, my object being to provide a structure which can be readily and inexpensively made and assembled and will permit of easy repair should the occasion arise.

To these ends, and also to improve generally upon devices of the character indicated, my invention consists in the various 20 matter hereinafter described and claimed.

In the accompanying drawings, Figure 1 is an elevation, chiefly in longitudinal section; Figure 2 is an elevation, partly in 25 section, on about the line 2-2 of Figure 1 looking in the direction of the arrows; Figure 3 is a similar view on about the line 3-3 of Figure 1; and Figures 4 and 5 are enlarged, fragmentary, detail views.

Referring now more particularly to these drawings, 1 indicates a hub shell, which may be the hub of the forward, driving wheel of a child's velocipede of well known construction, and 2 indicates the axle or crank shaft, which is the driver of such a device. This shaft is here shown as broken at its 35 ends but it commonly extends beyond such broken ends and is rotatably mounted in the front forks of the velocipede, pedal cranks being fastened to such shaft ends.

The shaft here illustrated has a brake anchor 3 of well-known construction surrounding it and held in place by a brake 40 arm 4 adapted to be fastened to one of the frame bars of the velocipede in a well understood manner, the anchor being prevented from outward longitudinal movement on the shaft by means of semi-cylindrical seg-

50 ments 5 fitting in a slot 6 about the circumference of the shaft and held against separation by an ordinary resilient split ring 7 which engages the reduced portions of those segments. Cooperating brake discs 8 and 55 9 of a well known construction have the

60 fingers of alternate discs extending into slots 10 in the inwardly projecting sleeve portion of the brake anchor while the outwardly extending fingers 11 of the other discs project into slots 12 which extend through the hub shell 1, this brake assembly 65 being well known and its operation being that when the discs are pressed together, as by the exertion of longitudinal pressure upon the thicker disc or brake actuator 13, the friction between these sets of discs serves to retard or stop the rotation of the hub shell, depending upon the pressure exerted.

Coarse threads 14 formed on the shaft 70 cooperate with corresponding threads 15 in the laterally shiftable connector 16, well understood in this art, about which is a lag spring 17 frictionally engaging the connector and having a hump or other projecting portion received in one of the slots 12. 75 A cone 18 is threaded upon the shaft and held in place by a lock washer 19 having a finger 20 entering a longitudinal slot 21 in the shaft, a lock nut 22 being screwed onto the shaft against this washer. The hub shell 80 1 is supported in a well understood manner upon the usual balls 23 and 24 bearing upon the before mentioned cone and upon a cone formed upon the before mentioned brake anchor, so that the hub shell 1 is free to 85 rotate on such bearings independently of the shaft 2, but can be braked when, by backward rotation of that shaft, the threads shift the connector 16 to the left and cause 90 it to engage the brake actuator 13 and press 95 the brake discs together as above indicated.

Provision is also made for clutching connection between the connector 16 and the hub shell so that when, upon forward rotation of the shaft 2, the connector is moved into clutching engagement with such hub-clutch element the continued rotation of the shaft causes the hub to be rotated by the rotating shaft and its connector 16.

According to my present invention the interior of the hub shell is provided with an annular, internal flange or abutment 25 to which the before mentioned slots 12 extend, these slots also conveniently extending through the flange so that the slots can be 100 made by a single, through travel of a cutter; and abutting against this flange is a separable clutch ring 26 which encircles the shaft 2 and has radially extending fingers 27 which are fairly closely received in the before 105 110

mentioned slots 12. In this way the clutch ring is held against rotation with respect to the hub shell, the fit of the fingers 27 in the slots 12 being sufficiently loose to permit the 5 ring to be readily slid into position from the brake end of the hub shell and yet being sufficiently close to prevent angular play between the ring and the hub shell. This ring is provided with means whereby it can be 10 clutchingly engaged by the driving end of the connector 16, and as here shown this means consists of teeth 28 on the inner face of the ring and adapted to be engaged by corresponding teeth 29 on the end of the 15 connector.

Such a clutch ring can be readily and inexpensively formed and hardened as a separate piece and then inserted into the hub shell, and it can also be readily replaced in 20 the event of breakage or wear. It will be noted, however, that in the structure here illustrated this ring abuts against the hub-flange 25 so that it is out of contact with any part that is stationary when the hub is 25 coasting, and, therefore, notwithstanding the use of this independently-made and separable ring, it has a firm seat in definite relationship to the driven hub shell and produces no drag upon that hub during the coasting 30 action.

I claim:

1. In a device of the character indicated, a driven member, a driver therefor, a laterally shiftable connector having operative 35 connection with said driver, and a separable clutch element slideable upon said driven member and in driving connection therewith and cooperating with said connector for driving said driven member, said clutch element being free from contact with relatively 40

stationary portions of the device; substantially as described.

2. In a device of the character indicated, a driven member provided with an abutment, a driver for said driven member, a laterally shiftable connector having operative connection with said driver, and a separable clutch element slideable upon said driven member and in driving connection therewith, said clutch element being between said abutment and said connector; substantially as described. 45 50

3. In a device of the character indicated, a driven member having an interior flange, a driver within said driven member, a laterally shiftable connector having operative connection with said driver, and a separable clutch element in driving connection with said driven member, said clutch element being between said flange and said connector; substantially as described. 55 60

4. In a device of the character indicated, a hub shell, supports therefor, an internal flange upon said hub shell and out of contact with said supports, said hub shell having interior longitudinal slots extending to said flange, a driver in said hub shell, brake elements in said hub shell having parts received in said slots, a laterally shiftable connector in said hub shell and about said driver and in operative connection with the latter, and a separable clutch member about said driver and having portions received in said slots, said clutch member abutting against said flange and being between said flange and said connector; substantially as described. 65 70 75

In testimony whereof I hereunto affix my signature.

CHARLES B. SIMMONS.
